Company, Gates, N. Y., a corporation of New
York

Application April 26, 1922. Serial No. 556,714

75 Claims. (Cl. 246—63)

This invention relates to the method and means for transmitting control influences for automatic train control systems.

In automatic train control systems, it is necessary to transmit control influences from the trackway to a passing vehicle in response to the change of traffic conditions in advance. In systems of this kind, it is desirable to provide such a transmitting means which is continuous in its character, that is, one in which the control influence is always present except when a danger traffic condition exists. Some of the advantages of continuous control are that when danger traffic conditions in advance clear up, the train is permitted to accelerate at the moment such change of traffic condition takes place; and further, if the trackway in advance of the vehicle should change from a certain condition to a more dangerous condition, such change will be transmitted to the vehicle immediately, thereby governing it accordingly. A further and important feature of a train control system of the continuous type is that it carries out the maxim of having the failure on the side of safety, that is, the communicating means is what permits the train to proceed, and consequently any failure thereof will control the train on the side of safety by causing it to stop or be otherwise subjected to the control corresponding to danger ahead.

A continuous control system is preferably of the type in which an influence is communicated in an occupied block and on account of this requirement, it is desirable to have current flowing in a circuit including the track rails in such a way that this current may be shunted by another train in said block and cut off from the following train. Along this line it has been proposed to supply alternating signaling current along the track rails and provide means for detecting its presence and its character. One objection to a system of this kind is the necessity of supplying a source of alternating current at all points along the track where such continuous control is to be effected. For this reason a failure of the necessary transmission lines, due to storms, sleet, lightning, and the like, often disables a considerable stretch of the system. Also, systems of this kind are rather expensive to install where direct current block signaling systems have already been installed, because an additional supply of alternating current solely for train control purposes must be added.

Among the principal objects and purposes of the present invention, are to devise a method

and means of providing continuous control and release inductively from the trackway to moving trains, which will have all of the advantages of a continuous inductive control system but will not require a supply of alternating current along the track, so that the system of train control may be readily applied to direct current block signal systems without expensive additions or modifications, and so that failures of the trackway equipment will be localized and will affect the movement of trains in the particular defective track circuit or block only.

Generally stated, the underlying principle of the method and means of this invention consists in utilizing a suitable supply of energy carried wholly on the train itself to produce by induction in regular track rails a signaling current which is controlled or modified automatically in accordance with the presence or absence of another train ahead, either directly through the shunting action of the wheels and axles of that train ahead, or through the agency of well-known track circuits; and this current, when thus controlled or modified to conform with clear or caution traffic conditions ahead, as the case may be, is again inductively taken up on the same train, amplified as required, and finally used to influence electro-responsive means and manifest by such influence the nature of the traffic conditions ahead, whether proceed, caution, or stop. Various specific characteristic features of the invention involved in carrying out this general principle of operation will be explained as the description progresses.

In describing the invention in detail, reference will be made to the accompanying drawings which show the invention in a simplified manner, more for the purpose of making it easy to understand its principle and mode of operation than with a view of illustrating the particular parts and circuits preferably employed in practice, and in which:—

Figure 1 diagrammatically illustrates one embodiment of the present invention, in which two-condition control of clear or danger is obtained;

Fig. 2 is a diagrammatic sectional view taken through the trackway directly ahead of the receiving elements of Fig. 1;

Fig. 3 illustrates another form of the invention, in which three-condition continuous control, corresponding to clear, caution, and stop, may be obtained in a territory having either direct or alternating current track circuits and with either end of the vehicle running ahead;

Fig. 4 illustrates another form of the invention, in which current is induced into a circuit which

is independent of the running rails of the track-way;

Figs. 5, 6 and 7 show diagrammatically modified forms of inducing and receiving elements;

5 Fig. 8 illustrates still another form of the invention, in which current is induced into and received from the same circuit in the track rails;

10 Fig. 9 illustrates a trackway system employing partially alternating current track circuits and partially direct current track circuits, in which the trackway equipment is constructed and arranged to facilitate continuous train control in cooperation with the same car-carried apparatus.

15 In the embodiments of the invention illustrated, the transmission of the continuous control influences are produced by alternating current flowing in the track rails ahead of the train in each block of the usual block signaling system, 20 while the train is in that block. This alternating signaling current of each block is preferably modified or suitably controlled by a track circuit of the block next in advance so as to produce on the train an appropriate influence corresponding 25 to the presence or absence of another train ahead. Various arrangements of track and control circuits suitable for controlling the flow of this alternating current may be employed, and it should be understood that the arrangement of 30 trackway circuits illustrated is merely a typical illustration.

In each of the embodiments of the invention illustrated, the track rails 1 and 2 are divided into blocks by insulated joints 3 in the usual way, one 35 block I and the adjacent ends of two other blocks H and J being shown. These parts and circuits associated with the various blocks, which are the same or function the same, have for convenience been given like reference characters, with distinctive exponents. Each of the blocks is provided with a source of current, as a track battery 4, and also a track relay 5, the same as in ordinary 40 block signal systems. The invention may be used with, or without, the usual fixed signals, dependent upon the type of train control apparatus; and we have illustrated such fixed signals S conventionally, without attempting to illustrate their 45 well-known control circuits and devices. In the various embodiments of the invention illustrated, 50 the normal direction of traffic has been indicated by a large arrow DT, substantially midway between the track rails.

Structure of Fig. 1.—In Fig. 1 has been illustrated a simplified arrangement for obtaining 55 continuous information and control on a train dependent on traffic conditions in advance thereof. In the simplified arrangement shown in this Fig. 1, only two-condition control is provided, that is, an indication of whether the block, in 60 which the train equipped with this apparatus is moving, is occupied by another train, or if the next block in advance thereof is occupied, or if both of these blocks are clear as far as the train in question is concerned. This continuous control is effected by inducing current in a loop circuit including the two rails of the trackway ahead of the train, which current, by the aid of a suitable transformer, will induce a current in a receiving 65 circuit, which comprises one of the rails and a return line wire, thereby permitting this latter current to be detected if traffic conditions ahead are clear.

70 Directly in front of the first axle of the vehicle are provided inducing elements IE. Each of these 75 elements, as shown, comprises a U-shaped lami-

nated core 6 terminating in enlarged pole pieces 7 and provided with a winding or coils 8. As shown, this winding for the core 6 comprises a coil on the back yoke and a coil on each of the upright legs. This particular winding arrangement has been shown with the idea that it utilizes to the best advantage the magneto-motive-forces of the winding and minimizes the disadvantages of leakage. Obviously, the winding may extend throughout the length of the core, if desired, or may be local on the legs or back yoke, accordingly as best suited for the particular working conditions encountered. The coils 8 of the inducing elements IE are preferably wound and are connected in series in a manner so that, if alternating current is supplied thereto, the flux emanating from the pole pieces 7 will encircle the track rails 1 and 2 in different directions, that is, so that one element at a given instant will induce a voltage in its corresponding rail directed away from the train, whereas the other element will induce a voltage in its rail directed toward the vehicle. This circuit for coils 8 is energized from a suitable alternating current generator 9, and may be traced as follows:—Beginning at the terminal or brush 10 of the alternating current generator 9, wire 11, coils 8 of one of the inducing elements IE, wire 12, coils 8 of the other inducing element IE, wire 13 back to the other terminal or brush 14 of the generator 9.

This alternating current generator 9 is preferably designed and operated to produce a frequency, distinctive from commercial frequencies, and reasonably high, which may for example be about 500 cycles per second, although, this frequency may, it is believed, be higher or lower, ranging for instance from 60 cycles to 3000 cycles per second. The reason for preferably employing a higher frequency than the usual lighting and power frequency, is that it facilitates the induction of voltage into a circuit, and also permits the detection of such current by induction through an intervening air gap much more effectively than does a lower frequency. The frequency employed should, however, be selected with due regard to the fact that the inductive reactance of the rails increases with the frequency and therefore hinders the transmission of high frequency current therethrough. The alternating current generator 9 may be driven by a turbine receiving steam from the locomotive, or it may comprise the generator of a motor generator-set running off of a battery floated across a source of direct current supply. If desired, two such sets may be provided to insure a continuous supply of alternating current.

The circuit in which current flows due to the action of these inducing elements IE, which for convenience will be termed a loop circuit herein-after, may be traced as follows:—Beginning at the 135 track rail 1, battery 4, primary winding 15 of the transformer P, track rail 2, wheels and axle 16 of the vehicle equipped with this train control apparatus and back to the track rail 1 of the trackway. For convenience the instantaneous direction of current flowing in this loop circuit has been indicated by solid arrows.

The flow of this current through the primary winding 15 of the transformer P induces a secondary or receiving current in a circuit, which may be traced as follows:—Beginning at the secondary winding 17 of the transformer P, wire 18, front contact 19¹, wire 20¹, condenser 21, wire 22, track rail 1, wire 23 back to the secondary coil 17 of the transformer P, the instantaneous direc- 150

tion of flow of this current being represented by the dotted arrows. This transformer may be of any construction suitable for the transformation of current of the signaling frequency used. The 5 ratio of transformation in the transformer P should be selected or varied in practical operation to fit the specific working conditions encountered.

It should be noted that, if a train employing a 10 plurality of cars is passing along the track, part of this current may flow through the rear axles of the train across between the rails, so that there may be some current in both of the track rails 1 and 2 at the rear end of the locomotive; and in order to detect all of this current two receiving 15 elements RE have been provided.

Each of these receiving elements RE comprises a U-shaped core 24, preferably constructed of a high grade of laminated iron, which terminates in enlarged pole pieces 25, and is provided with a 20 winding or coils 26. The coils 26 of these receiving elements RE are preferably connected in series so that the voltages induced therein, due to the magnetism caused by the current flowing in the receiving circuit, that is, the current flowing in the 25 two rails in multiple, will be cumulative. In order to improve the functioning of this receiving element, and also to segregate and avoid amplification of currents of frequency somewhat different from the specific signaling frequency of 30 the train in question, a condenser 27 is preferably connected in multiple with the coils of said element; and this complete receiving circuit, comprising wires 28, 29, 30 and condenser 27, is connected to an input circuit, which includes wires 35 31 and 32, of a suitable amplifying organization or device, designated as a whole A.

This amplifying device A may be of any desired type and may employ any number of stages of amplification, but has for simplicity been shown 40 as a two-stage amplifier set, employing two thermionic or vacuum tube amplifiers of the three-element type, which for convenience will be termed audions. The audion 33 is provided with a filament 34, a grid 35, and a plate 36; and the audion 37 is similarly provided with a filament 38, a grid 39, and a plate 40. The filaments 34 and 38 are heated by a filament battery 41. The wire 31 is connected to the filament 34, and the other wire 32 is connected to the grid 35, through blocking condenser 44 and wire 45. This blocking condenser 44, serves its usual purpose, familiar to those skilled in the art. A grid-leak, comprising a high ohmic resistance, across this condenser or inserted between the grid 35 and the filament 34, 50 together with other expedients well-known by those skilled in the art pertaining to amplifiers of this kind, may be employed.

The plate circuit of the audion 33 may be traced as follows:—Beginning at the filament 34, wire 60 46, plate battery 47, wire 48, primary winding 49 of the transformer T, wire 50, plate 36, through the audion back to the filament 34.

The grid circuit of the audion 37 may be traced as follows:—Beginning at the filament 38, wire 51, 65 secondary winding 52 of the transformer T, wire 53, to the grid 39 of the audion 37.

The plate circuit of the audion 37, or output circuit of the amplifying combination, may be traced as follows:—Beginning at the filament 38 70 of the audion 37, wires 54 and 46, plate battery 47, wires 55 and 56, to a suitable electro-responsive device, which in this instance comprises one winding 57 of a relay R, wires 58 and 59, plate 40 back to the filament 38. A condenser 43 is preferably connected across the field winding 57 of

the relay R to balance its inductive reactance; and this condenser is selected or adjusted in practice to tune the circuit for said field coil to resonance for the particular signaling frequency of the train in question.

The other or "local" field 60 of the relay R is energized by the alternating current generator 9, through a circuit which may be traced as follows:—Beginning at the terminal 10 of the generator 9, wire 61, local field winding 60 of the relay R, wire 62 back to the terminal 14 of the generator 9.

The relay R may take various forms; and as shown conventionally, it is a two-element alternating current relay, either of the vane or induction type, commonly used in the railway signaling art. It should be understood, however, that it is contemplated in connection with this invention that relays of the dynamometer type, or in fact any form of electro-responsive device suitable for the purpose and having the desired efficiency of performance, may be used. In the type of relay shown, the torque or operating force ceases when current is cut off from one field, even though the other field may still be energized. 100 Also, this relay requires a certain degree of phase displacement of the currents in its two-field windings to produce a torque. These, and other operating and structural characteristics of the two-element alternating current relay employed, are 105 well recognized in the art. When used in connection with this particular invention, such two-element relay is preferably designed in accordance with well-known principles to derive most of its operating energy from its so-called local 110 field winding, that is, the winding which is directly energized from the generator. This is done so that the amount of energy needed in the other field winding for operating the relay, which is derived from the trackway, may be relatively 115 small. This relay R is provided with a suitable circuit controlling arrangement and in accordance with well-known practice has a bias to the neutral or deenergized position. In the simplified arrangement shown, the movable element or 120 contact finger of the relay is biased by a spring. In practicing the invention it should also be borne in mind that the relay, together with the other sensitive parts of the car equipment, should be suitably housed and protected against jar and 125 vibration; but since these specific expedients form no part of the present invention, illustration and description thereof has been omitted.

When the relay R is energized, a circuit is maintained closed through the train control device K, which may be traced as follows:—Beginning at the battery 65, wire 66, movable contact 67 of the relay R, wire 68, winding of the train control device K, wire 69 back to the battery 65, thus maintaining a suitable train control device K energized so long as the relay R is energized. This train control device, when it has been deenergized by the dropping of the relay R, may be used to apply the brakes at once, or give a brake application dependent upon the 140 speed of the train at the time, the acceleration or deceleration of the train, or whether the brakes are applied at the time, and the like. In short, the device K, when deenergized, may impose any form of control desired, or merely give a warning 145 signal. Since, however, the particular construction of this train control device is no part of the present invention, such a device has been merely conventionally illustrated.

Operation of Fig. 1.—Let us assume that a 150

vehicle is moving in the block I under clear traffic conditions ahead in the block I as well as in the block J, as illustrated. Under these conditions, the inducing elements IE will induce a current in the loop circuit as illustrated by the solid arrows which in turn, through the windings 15 and 17 of the transformer P, will cause the flow of a current, as indicated by the dotted arrows in the receiving circuit. This current in the receiving circuit will induce a current in the coils 26 of the receiving elements RE which, by the aid of the condenser 27 and the blocking condenser 44, will impress a voltage on the grid 35 of the audion 33 corresponding to the current flowing in the receiving circuit just mentioned. The impression of this voltage on the grid 35 causes the internal resistance of the plate circuit of the audion 33 to change substantially proportionally, thereby causing the flow of a pulsating current in this plate circuit. This current will be transformed through the transformer T, thereby impressing a voltage on the grid 39 of the audion 37 which has a definite phase relation with respect to the voltage impressed on the grid 35, but is highly magnified or amplified. The impression of this highly amplified voltage on the grid 39 causes a pulsating current to flow in the plate circuit of this audion 37, which includes the secondary field winding 57 of the relay R. This pulsating current will act on the current flowing in the local field 60 of this relay R to produce a torque to maintain movable contact 67 closed against the tension of the spring 70 of this relay, thereby maintaining the train control device K energized and ineffective to restrict the speed of the train.

As previously stated, the two-element type of induction relay R assumed to be used requires a phase displacement of the currents in its field windings to produce an operating torque. This desired phase displacement is obtained by properly designing or proportioning the circuits over which current is supplied to the field windings from the generator 9. One field winding 60 is directly connected to the generator; and assuming the current in this field winding 60 to be in phase with the voltage of the generator, the desired phase displacement for operation of the relay R may be obtained by causing the current in the other field winding 57 to lag through the desired angle, preferably 90 electrical degrees, by making reactive any of the circuits or electrical connections intervening between the generator and the field winding 57.

Let us assume, now, that the block J is occupied when the train in question enters the block I. The train in the block J robs the track relay 5¹ of its current, thereby causing it to drop its front contact 19¹, thus opening the receiving circuit heretofore traced. Obviously, since this receiving circuit has been entirely interrupted, the receiving elements RE will not be influenced and the relay R will be deenergized, thus deenergizing the train control device K, which will restrict the movement of the train in a manner dependent upon the construction of this device K.

Let us assume, now, that the block I is occupied by another train ahead at the time the train in question equipped with the apparatus illustrated is entering the block I. Under this condition, the train ahead occupying the loop circuit in front of the train in question shunts the primary winding 15 of the transformer P, thereby preventing the flow of current in the receiving circuit entirely, or at least diminishing its flow to an extent so that the relay R will be deener-

gized, thus actuating the train control device K in the same manner as heretofore set forth.

Let us assume, now, that the train ahead occupying the loop circuit ahead of the train in question leaves the block I and enters the block J. Although the transformer P is no longer shunted, no clearing influence will be received at the control relay R, because the receiving circuit is open at the front contact 19¹ of track relay 5¹.

Let us assume, now, that this train ahead entirely leaves the block J. This will cause the track relay 5¹ to become energized, thereby closing its front contacts 19¹ and transmitting a clearing influence at the instant traffic conditions ahead clear up which influence will again energize the relay R, and permit the train to proceed unrestricted immediately.

The condenser 21 has been provided in the receiving circuit for the purpose of insulating the opposite ends of the track rail 1 of a particular block, except through this rail itself, so that if a rail should break, direct current can not flow through the wire 22 to energize the track relay 5, for the flow of such current would destroy the check on the integrity of the rail circuit afforded by the usual track circuit. It should, however, be understood that a resistance or impedance may be substituted for the condenser 21, if desired, this resistance or impedance being of a value to limit the flow of direct current to an amount insufficient to energize the track relay 5.

Although a two-element relay R has been shown, it should be understood that a single element relay energized entirely by the receiving elements RE through suitable amplifiers may be employed. A single element relay may, under certain conditions, be preferable, because the functioning of a relay of this type is entirely independent of phase relation, which is a variable factor, depending upon the position of train in the block and upon the condition of the track circuit. Where a two-element relay of the induction type is used, as shown, the currents in the two fields of this relay should have a maximum phase displacement for efficient operation. Special provisions for obtaining such phase displacement may be made wholly on the train, wholly on the track, or partly on both. Also, if desired, the generator may have a separate phase winding thereon, for the purpose of energizing the local field of the relay. Generally speaking, it is considered preferable to have some at least of the phase displacement, in addition to that caused by the inherent reactance of the track rails, obtained by devices wholly on the track, since this facilitates adjustment and compensation for different length blocks, different conditions of ballast, and the like.

Structure of Fig. 3.—In Fig. 3 of the drawings has been illustrated a modified form of the invention shown in Fig. 1. Since certain of the elements are the same as those illustrated in Fig. 1, they will be given like reference characters. The trackway apparatus of the block I is in many respects similar to that of the apparatus illustrated in Fig. 1, the principal distinction being that the line circuit is connected to the middle point of a balancing resistance BR at each end of the block instead of being connected to the track rail 1; and that provision has been made for changing the relative instantaneous rail polarity of the receiving circuit with respect to the loop circuit by pole-changing contacts actuated by the relay 5¹. In order to facilitate the movement of the locomotive or other vehicle

carrying the inducing elements IE at the front end and the receiving elements at the rear end, past the insulated joints at the entrance to a block without interruption of the continuous influence, provision is preferably made to extend, so to speak, the receiving circuit of each block back for a short distance at the exit end of the block next in the rear, so that at the time the inducing element of the vehicle passes the joints, the receiving element of that vehicle may be influenced by the current in the receiving circuit of the block the vehicle is just entering. This may be done, as shown, by making the connections between the track rails and the balancing resistance BR at the entrance end to each block by conductors extending back of the insulated joints of that block close to and parallel with the track rails so as to affect the receiving elements. These conductors may be lengths of insulated wires fastened directly to the track rails, or may be sections of additional track rails, or the like. The length of these auxiliary conductors should correspond approximately with the distance between the inducing element and receiving element on a locomotive.

It is noted here that this same expedient may be added to the arrangement shown in Fig. 1, and also that such overlapping of conductors may be altogether omitted, if desired, and satisfactory operation obtained provided the train control device K, or some element of its control means, is made sufficiently slow acting to avoid the imposition of an unfavorable control during the time the insulated joints bar the flow of current from the inducing elements to the receiving elements.

This receiving circuit may be traced as follows:—Beginning at the secondary winding 17 of the transformer P, wire 75, front contact 76¹, wire 77¹, wire 78 to the middle point of balancing resistance BR, through the track rails 1 and 2 in multiple to the balancing resistance BR at the exit end of the block, through wire 79, front contact 80¹, wire 81 back to the secondary winding 17 of the transformer P.

It is considered that the system of this invention, employing a source of alternating current on the car, is specially adapted for territory equipped with direct current track circuits, since it permits the application of a train control system of the continuous inductive type to such direct current territory without need of adding expensive trackway sources of energy. However, on those railroads or divisions where alternating current track circuits are used, or where a suitable reliable source of alternating current along the track is already available, it might be considered preferable to use the alternating current already at hand for train control purposes; but since it may be necessary for the same locomotive or other vehicle to travel in both the direct current and alternating current territories, it is proposed here to provide a form of car apparatus which will be readily converted so as to work in either territory. To facilitate explanation of this feature of the invention, the block J has been shown in Fig. 3 as having an alternating current track circuit supplied from a transmission line 82¹ along the track, it being expected that energy 82¹ from this transmission line will be used for train control purposes.

In the block J has been illustrated a transmission line, comprising wires 82¹ which are connected to the primary winding 83¹ of a suitable transformer. This transformer is provided with

two secondary windings, one of which, namely, winding 84¹, is used for energizing the loop or track circuit, whereas the other winding 85¹ is used for energizing the receiving circuit heretofore mentioned. The instantaneous current flowing in the track circuit will be illustrated by solid arrows, whereas the current flowing in the receiving circuit will be indicated by dotted arrows. The track circuit may be traced as follows:—Beginning at the secondary winding 84¹, wire 74¹, 85 track rail 2, track relay 5¹, rail 1, wire 86¹, adjustable impedance 87¹ back to the secondary winding 84¹.

The receiving circuit may be traced as follows:—Beginning at the secondary transformer winding 85¹, wire 88¹, movable contact 89², wire 90¹ to the middle point of the balancing resistance BR¹, through track rails 1 and 2 in multiple, to the middle point of the other balancing resistance BR¹ at the exit end of the block, wire 91¹, front contact 92², wires 93¹ and 94¹ back to the secondary transformer winding 85¹.

It is thus noted that under clear traffic conditions of the block J, two independent alternating currents will be flowing in the track rails of the block, one of these currents flowing in opposite directions in the rails, whereas the other current flows in the same direction through the rails in multiple. These currents preferably have their phases displaced substantially 90 degrees, such displacement being accomplished by inserting resistances in one of the inductive reactive circuits, preferably the receiving circuit, or if desired these circuits may be energized from different phases of a polyphase transmission line.

The car-carried apparatus illustrated in Fig. 3 is of a character so that if direct current block signal territory is encountered, a suitable double-throw switch DS may be closed in one direction, whereby train control influence communicating 115 means is provided which operates on the principle wherein the energy is supplied from the train, similar to that illustrated in Fig. 1; whereas if this double-throw switch DS is thrown to the opposite position the car-carried apparatus will 120 comprise two receiving devices, one of which is adapted to pick up the current flowing in the loop circuit of an alternating current track circuit, that is, a current flowing in the opposite direction in the two rails, and the other receiving device being employed to detect the current flowing in the receiving circuit, or in the same direction in both rails in multiple.

The car-carried apparatus will first be described with the double-throw switch DS in the 130 position illustrated, that is, for accomplishing train control in direct current block signal territory, such as the block I. The circuit for energizing the inducing elements IE may be traced as follows:—Beginning at the terminal 10 of the 135 generator 9, wire 95, switch blade 96, to the generating or inducing bus IB, wire 97, switch blade 98, wire 99, coil 8 of the inducing element IE, wire 100, switch blade 101, wire 102 back to the inducing bus IB, to switch blade 103, wires 104 140 and 105 back to the terminal 14 of the alternating current generator 9; and a partial circuit also connected across the inducing bus IB, which may be traced as follows:—Beginning at the inducing bus IB, wire 106, switch blade 107, wire 108, coil 145 8 of the other inducing element, wires 109 and 100, switch blade 101, wire 102 back to the inducing bus IB.

The flow of the current in the loop circuit, due to the induction elements IE, causes a current to 150

flow in the receiving circuit by transformer action through the transformer P, which in turn induces a voltage in the receiving elements RE, which is impressed upon the amplifying device A. This circuit through the coils of the receiving elements RE may be traced as follows:—Beginning at the inlet wire 31 of the amplifying device A, through the one wire of the receiving bus RB, wire 110, switch blade 111, wire 112, receiving coil 26 of one 5 of the receiving elements RE, wires 113 and 114, coil 26 of the other receiving element, wire 115, switch blade 116, wire 117 back through the other wire of the receiving bus RB, to the other inlet wire 32 of the amplifying device A. A condenser 10 42 of the proper capacity is connected across the coils of the receiving elements for tuning purposes.

The voltage induced in the receiving elements RE will cause a current to flow in the secondary 20 field winding 57 of the relay R, thereby maintaining the relay energized in the direction as indicated in the drawings, the other or local field winding 60 of this relay R being energized by the alternating current generator 9 through the following circuit:—Beginning at the terminal 10 of the generator 9, wire 95, switch blade 118, wire 119, local field winding 60 of the relay R, wire 120, switch blade 121, wires 122 and 105 back to the terminal 14 of the alternating current generator 30 tor 9.

With the relay R energized in the normal or clear traffic condition, as indicated in the drawings, a circuit for energizing the green lamp G may be traced as follows:—Beginning at the 35 battery 125, wire 126, movable contact 127 of the relay R, stationary contact 128, a green or clear indication lamp G, wires 129 and 130 back to the battery 125.

Under this, the clear traffic condition, a circuit 40 for energizing the cautionary train control device K will be energized through a circuit, which may be traced as follows:—Beginning at the battery 125, wire 126, movable contact 127 of the relay R, stationary contact 128, wire 131, 45 cautionary train control device K, wires 132, 133 and 130 back to the battery 125.

Under this same condition, a circuit may be traced through a danger train control device D, as follows:—Beginning at the battery 125, wires 50 126 and 134, movable contact 135, stationary contact 136, wire 137, danger train control device D, wires 138, 139, 133 and 130 back to the battery 125. Therefore, under the clear traffic condition, both the cautionary train control device K and the danger train control device D will be energized, and the clear indication lamp G will be illuminated.

Operation.—Let us assume that a train 60 equipped with the apparatus illustrated in Fig. 3 is moving in the block I with no other train ahead of it in said block, and also with the block J unoccupied, that is, is moving in block I under clear traffic conditions. Under this condition, the relay R will be energized with its movable contacts in the position illustrated in the drawings, thereby permitting the train to proceed 65 without restriction substantially in the same manner as described in connection with the apparatus illustrated in Fig. 1.

Let us, now, assume that the block J is occupied when the train in question enters the block I. The presence of a train in the block J causes the alternating current track relay 5¹ to be de- 70 energized, causing it to drop its front contacts

76¹ and 80¹, thereby reversing the connections and the instantaneous polarity of the current in the receiving circuit. The reversal of the instantaneous polarity of the current in the receiving circuit relative to that of the alternating current generator 9, causes the torque produced by the relay R to be in the reversed direction, thereby swinging the movable contacts 127 and 135 to the other extreme position, thereby interrupting the circuits through the clear indicating lamp G and the cautionary train control device K, and completing a circuit through the caution indicating or yellow lamp Y. This latter circuit may be traced as follows:—Beginning at the battery 125, wire 126, movable contact 127, wire 140, caution indicating lamp Y, wires 141, 142, 139, 133 and 130 back to the battery 125. This causes the train to be automatically controlled in accordance with the restriction of the cautionary train control device K, and advises the engineer that he is now occupying a caution block, this being manifested by the illumination of the yellow lamp Y and the extinction of the green lamp G. The required phase relation between the currents in the two phases of the relay R, for proper functioning of this device, may be obtained by adjusting the phase relation on the vehicle, or in each block along the trackway in any suitable manner as desired.

Let us, now, assume that the train in question 105 is entering the block I when this block is occupied by another train. Under this condition, the transformer P will be deprived of the current flowing in the loop circuit, because this current is now flowing through the axles of said another train ahead. Consequently, the generator 9 on the following train is unable to provide current for the receiving circuit, comprising the track rails 1 and 2 in multiple, which results in the deenergization of one field of the relay R, thereby causing its movable contacts 127 and 135 to assume their intermediate or neutral position due to the inherent bias of the relay, as common in relays of this type. At this position of the relay, both the cautionary train control device 110 K and the danger train control device D, will be deenergized and likewise the clear or green lamp and the caution or yellow lamp, will be deenergized, and the red or danger lamp will be energized through a circuit, which may be traced as 115 follows:—Beginning at the battery 125, wire 126, movable contact 127, stationary contact 143, red or danger lamp RL, wires 144, 142, 139, 133 and 130 back to the battery 125. This advises the engineer that he is now occupying a danger 120 or occupied block.

It should be noted that the circuit for energizing the danger train control device D is momentarily interrupted during the time the relay R changes from its clear to its caution position. 135 This momentary interruption of the circuit through this train control device D, however, may be made ineffectual by constructing this device to be slow acting to an extent to allow such movement of the relay from its one extreme to its other extreme position before said device operates effectively.

Let us, now, assume that under clear traffic conditions the vehicle, moving in block I with its train control apparatus in its normal condition, enters the block J. If the engineer does not operate the double-throw switch DS, the relay R will be deenergized, because the current induced in the loop circuit ahead of the train does not produce a corresponding current in the re- 140 145 150

ceiving circuit, assuming the track transformer to have a relatively high reactance for the train control frequency. This deenergizes the cautionary train control device K and the danger train control device D, and further energizes the red or danger lamp RL and deenergizes the green lamp G, with the result that the engineer knows that either the block J has suddenly become a danger block or he has entered alternating current block signal territory. In other words, the relay R becomes deenergized, because one of the fields is energized by current from the alternating current generator 9, and the other field is energized from the transmission line 82¹. If the engineer throws the double-throw switch DS to the dotted position and traffic conditions ahead in the block J and in the block K are clear, the relay R will again be energized to its clear indicating position.

The circuit for energizing the phase winding 57 of the relay R in an alternating current block, with the switch DS thrown to the dotted position, is the same as heretofore described and need not again be traced. The local phase winding 60 of the relay R will under this condition be energized through a circuit, which may be traced as follows:—Beginning at the coil of one of the inducing elements IE, wire 99, switch blade 98, wire 97, inducing bus wire IB, switch blade 96, wire 150, through the amplifying apparatus A^a, wire 151, switch blade 118, wire 119, local field winding 60 of the relay R, wire 120, switch blade 121, wire 152 back through the amplifying apparatus A^a, wire 153, switch blade 103, other wire of the inducing bus IB, wire 102, switch blade 101, wire 100 and back to the coil 8 of the inducing element IE; and in multiple with the coil 8 just mentioned is a partial circuit through the other inducing element IE, which may be traced as follows:—Beginning at the inducing bus IB, wire 102, switch blade 101, wires 100 and 109, coil 8 of the other inducing element IE, wire 108, switch blade 107, wire 106 back to the inducing bus IB. In order to properly tune this circuit for the frequency employed condensers 123 and 124 have been provided.

The alternating current flowing down one rail 2 and back through the other rail 1 of the block J, as indicated by the solid arrows, which is derived from the transmission line 82¹, is therefore detected by the elements IE heretofore referred to as inducing elements, then amplified by the amplifying device A^a and transmitted to the field winding 60 of the relay R; whereas the current flowing in the same direction in the two rails 1 and 2, as indicated by the dotted arrows, is picked up by the receiving elements RE in back of the tender, then amplified and transmitted to the other field winding 57 of the relay R.

For an induction type relay, these currents preferably have their phase relation so adjusted that one of them lags substantially 90 electrical degrees behind the other. This may be accomplished by inserting resistance or inductive reactance in one of the phases, or it may be accomplished by transmitting polyphase currents along the trackway and by energizing the loop circuit by one phase of the polyphase transmission line source, and energizing the receiving circuit by another phase of said source of energy.

Let us, now, assume that this train enters the block J when the block K is occupied. The block K, now being occupied, causes the track relay 52 to be deenergized for reasons heretofore given, thereby reversing the polarity of the receiving

circuit heretofore traced. Since the instantaneous direction of flow of current in the receiving circuit, as indicated by the dotted arrows, is now reversed, it is obvious that the current flowing in the field 57 of the relay R which is due to a current in the receiving track circuit, will also be reversed with respect to the current flowing in the other field 60 of this relay. Consequently, the torque produced by the relay R will be reversed, thus swinging the movable contacts 127 and 135 to the other extreme position. This will deenergize the green lamp G and the cautionary train control device K, and will energize the yellow or caution lamp Y for reasons described in detail in connection with the operation of the train control device in the block I.

Let us, now, assume that the train enters the block J when this block is occupied by another train ahead. Under this condition, current will be flowing in the field winding 57 of the relay R due to current flowing in the receiving track circuit of the block J, and this current and its phase relation will depend on whether the block K is occupied or not. The phase relation of this current is, however, immaterial at this time, because the other field 60 of the relay R will be entirely deenergized, because the current flowing in the loop circuit ahead of the train in question will not reach this latter train at all, but will flow through the axles of the train nearest the exit end of the block J. The field 60 now being entirely deenergized will cause the relay R to assume its neutral or deenergized position, thereby deenergizing both the cautionary train control device K and the danger train control device D, and at the same time extinguishing the lamp G and illuminating the danger or red lamp RL.

Automatic reversing switch.—In order to permit the vehicle, equipped with train control apparatus illustrated in Fig. 3, to move with either end leading or ahead, that is, if the equipment in question is mounted on a locomotive and tender, to permit this equipment to run either pilot or tender first, without duplicating the receiving apparatus, an automatic reversing switch has been provided which automatically changes the receiving elements RE to inducing elements and changes the inducing elements IE to receiving elements, changes in the coils being also made if found desirable. As shown, the receiving elements RE and the inducing elements IE are assumed to be identical in design, those mounted in front of the vehicle being connected in multiple and serving as inducing elements, whereas those mounted at the rear of the tender are connected in series and serve as receiving elements.

The automatic switch operator for actuating the switch blades 98, 101, 107, 116, 156 and 111 comprises a hub 157 mounted on the axle 158 of the railway vehicle. This hub 157 is provided with an extending arm 159 having a perforated lug 160 extending therefrom. A brake-shoe 161 provided with a rod 162 extending through the perforation of the lug 160 is provided. On the rod 162 between the brake-shoe 161 and the lug 160 is a spring 163 which urges the brake-shoe 161 against the axle 158, thus providing frictional engagement between the arm 159 and the car axle. By looking at the drawings, it is obvious that if the vehicle is moving in the normal direction of traffic from left to right, as indicated by the large arrow in block I, the axle will be turned clockwise, as indicated by the arrow 164, thus moving switch rod 165 to place 166

the switch blades 98, 101, 107, 116, 156 and 111 in the positions indicated. If now the vehicle moves in the opposite direction, these switch blades will assume the dotted position and complete the following partial circuits between the inducing and receiving elements IE and RE and the inducing bus and receiving bus IB and RB, respectively. These partial circuits may be traced as follows:—Beginning at the inducing bus IB, wire 166, switch blade 111, wire 112, coil 26, wire 113, wire 167, switch blade 156, wire 168; and another partial circuit as follows:—Beginning at the wire 168, switch blade 156, wires 167 and 114, coil 26, wire 115, switch blade 116, and wire 169. The partial circuit connected to the receiving bus RB under this condition may be traced as follows:—Beginning at the wire 170, switch blade 107, wire 108, coil 8, wire 109, other coil 8, wire 99, switch blade 98, and wire 171.

By studying the devices thus far described in connection with Fig. 3, it is apparent that, if the engine equipment employing the train control devices illustrated, is pushing a train ahead of it in the normal direction of traffic, with either the tender or the pilot leading, or if a train with the engine ahead as usual and running in the normal direction of traffic should back up, in each of these instances on account of the operation of the automatic reversing switch, the inducing elements IE for the system having a source of energy on the vehicle will be at that end of the locomotive where the cars that it is pushing are, therefore the energy supplied to the loop circuit will flow through the axles of said car and will not reach the transformer P to be transmitted into the receiving circuit. The same is true if a train, with the engine leading, should run in a direction opposite to the normal direction of traffic. On the other hand, if the train is making such moves in a block, such as the block J, where the source of energy is located along the trackway, the inducing elements which now serve as receiving elements to pick up current flowing in opposite directions in the two rails, will be at the rear of the tender and will therefore be unable to pick up such current, since this current will be shunted by the axles of the locomotive and tender.

In order that a locomotive may make the peculiar movements just discussed, that is, push a train ahead of it, back-up, or run against the normal direction of traffic in systems which are signaled for only one direction of traffic, means are contemplated to permit safe movement of the train faster than ordinarily allowed with the danger train control device D actuated or deenergized. Such means has been provided, as illustrated, by the release device RD. This release device RD is one which must be continuously operated by the engineer to permit him to proceed at a speed higher than that permitted by the danger train control device D. This release device RD comprises a hand or treadle operated centrifugal switch, and has been illustrated as a spur gear 172 provided with a handle or treadle 173 pivotally mounted in any suitable manner and continuously in driving engagement with a pinion 174 keyed to a shaft 175. To this shaft is pinned a collar 183 which is mechanically connected to a shiftable disc 184 by links 185 and 186 having centrifugal weights 187 at their pivotal connection. The disc 184 is held away from the collar 183 by a compression spring 188. Adjacent the disc 184 is a stationary contact 179,

and a movable contact 178 having an insulating tip 189. Upon rotation of the shaft 175 the force, due to the centrifugal action of the weights 187, causes the disc 184 to slide sidewise and complete a circuit between the movable contact 178 and the stationary contact 179.

Let us assume, now, that the engineer is making a back-up move, or is moving against the normal direction of traffic. Such movement of a train is usually carried out by the authority 85 of written train orders. As soon as such a back-up move against the normal direction of traffic is made, the relay R will be deenergized for reasons heretofore stated, thereby limiting the speed or movement of the train in accordance with that permitted by the danger train control device D. If the engineer wishes to proceed, only restricted by the cautionary train control device K, he may do so by giving evidence of the fact that he is awake and aware of traffic conditions similar to 90 danger traffic conditions, by actuating the crank or treadle 173. The actuation of this treadle or crank 173 at a predetermined rate operates the shaft 175 at a speed to cause the centrifugal weights 187 to move further apart, thereby sliding 100 the disc 184 toward the collar 183, thus urging the movable contact 178 against the stationary contact 179. This will complete a circuit, which may be traced as follows:—Beginning at the battery 125, wires 126 and 134, movable contact 135, stationary contact 180, wire 181, movable contact 178, stationary contact 179, wires 182 and 137, danger train control device D, wires 138, 139, 133 and 130 back to the battery 125. The completion of this circuit energizes the danger train control device D, and permits the engineer to proceed restricted only by the cautionary train control device K.

Let us assume, now, that the engine and tender equipment is turned around, and is therefore running tender first in the direction of traffic. Under this condition, the automatic reversing switch will be moved to the dotted position, thereby changing the circuit connections to connect the inducing elements IE in series and the receiving elements RE in multiple, thereby connecting the leading elements which are located on the rear of the tender to the alternating current generator 9, and connecting the trailing elements mounted on the pilot end of the engine for detecting currents flowing in the same direction in the running rails, assuming direct current block signal territory, thus allowing the engineer to proceed in accordance with traffic conditions. The conditions, when moving in alternating current block signal territory, will be obvious to those skilled in the art from the discussion of the relation of the several devices, depending on the position of the double-throw switch DS as heretofore described.

It should be understood that if two-condition train control is to be accomplished with the apparatus illustrated in Fig. 3, that this may be done by substituting a simple single front contact for controlling the receiving circuit, for the double-pole double-throw contact actuated by the track relay 5, similar to the arrangement illustrated in Fig. 1. In practicing the invention as just described in connection with Fig. 3, although the frequency of the car-carried generator may 145 be the same as the alternating current signaling frequency, it is preferably different, and adjustable tuning devices are preferably employed to tune to this frequency or the commercial frequency.

Description of Fig. 4.—In Fig. 4 has been illustrated a modified form of the invention shown and described in connection with the block I of Fig. 3. The principal distinction of this embodiment over the one just described, is that the energy is transmitted from the train carried source to the transformer P located at the exit end of a block by an independent and insulated circuit, which for convenience will be called an inducing circuit, and the energy is picked up from the loop circuit comprising the track rails 1 and 2 ahead of the train. This inducing circuit may be traced as follows:—Beginning at the inducing wire 200, wire 201, stationary contact 202¹, front contact 203¹, wire 204, winding 17 of the transformer P, wire 205, front contact 206¹, stationary contact 207¹, line wire 208 back to the inducing wire 200.

In this form of the invention only a single inducing element IE is provided. This element IE, as shown, comprises a U-shaped laminated core 209 terminating in pole pieces 210 and having a coil 211. This inducing element IE is designed and constructed to properly cooperate with the inducing wire 200 and may have only a small air gap between the pole pieces 210 which must be traversed by the magnetic flux necessary to induce the desired voltage in the inducing circuit. This inducing element is energized by the alternating current generator 9, through a circuit which may be traced as follows:—Beginning at the terminal post 10 of the alternating current generator 9, wire 212, coil 211, wire 213 back to the other terminal 14 of the alternating current generator 9. This inducing circuit is preferably entirely insulated from the track circuit. Various arrangements for supporting the inducing wire along the trackway may be employed, for instance, a channel-like trough may be laid either between the rails or on the outside thereof and upon the ties for carrying a bare or weather-proof insulated wire over which an inducing element IE is adapted to pass, or a third rail of small cross-sectional area and preferably made of non-magnetic material may be used.

The local field winding 60 of the relay R is energized by the alternating current generator 9, through a circuit which may be traced as follows:—Beginning at the terminal 10 of the generator 9, wire 214, local field winding 60 of the relay R, wire 215 back to the terminal 14 of the alternating current generator 9.

The secondary field winding 57 of the relay R is energized by the coils 26 of the receiving elements RE and the amplifying device A, through a circuit which may be traced as follows:—Beginning at the coil 26 of one of the receiving elements RE, wire 216, coil 26 of the other receiving element, wire 217, through the amplifying device A, wire 218, secondary field winding 57 of the relay R, wire 219 back through the amplifying device A, wire 220 back to the coil 26 of the receiving element RE.

The devices controlled by the relay R are substantially the same as those described in connection with Fig. 3, and will therefore be given the same reference characters. Since the operation of this embodiment of the invention is substantially the same as that described in connection with Fig. 3, a description thereof is deemed unnecessary and will be omitted.

Description of Figs. 5, 6 and 7.—In Figs. 5, 6 and 7 have been illustrated several modified forms of inducing and receiving devices adapted for use in connection with trackway circuits, such

as illustrated in Figs. 1 and 3. The principal distinction of these modified forms of devices from those illustrated in Figs. 1 and 3, is that the receiving devices or elements RE are connected to detect or receive currents flowing in opposite directions in the running rails of the trackway, similar to the receiving elements RE illustrated in Fig. 4; and the inducing devices or inducing elements IE are designed and constructed to induce currents in the same direction in both of the track rails in multiple, which, by the aid of a return line wire and a transformer are adapted to produce current in the loop circuit comprising the usual track circuit.

In Fig. 5 such communicating devices, that is, devices in which current is induced in a circuit including both of the track rails in multiple, and in which current is detected in the loop circuit ahead of the train in a block, have been illustrated so that they may be substituted in the system illustrated in Fig. 3. In order to simplify the explanation of how the devices illustrated in Fig. 5 may be substituted for the inducing and receiving elements, shown in Fig. 3, the same reference characters, namely, 99, 100 and 108, 100 and 112, 167 and 115 have been assigned to the six lead-in wires of both of these sets of devices.

In this arrangement of communicating devices, assuming the direction of movement of the vehicle equipped therewith to be in the direction 105 of traffic, as indicated by the arrow DT, the inducing elements IE, which are assumed to be the same in construction as the receiving elements but are merely connected for inducing purposes while the train is moving in that direction, are 110 energized by the generator 9, as is obvious when tracing the energizing circuit in Fig. 3 in connection with the lead-in wires 99, 100 and 108 of Fig. 5. Under this condition, the traffic controlled 115 reversing switch RS is in the position as indicated in Fig. 3.

Current flowing in the circuit through the inducing elements IE just mentioned, will induce a voltage in the same direction in both of the running rails at a point between the tender, as 120 diagrammatically indicated by the wheels and axle 221, and a trailing train as diagrammatically indicated by the wheels and axle 222. It is apparent that, if such voltages are induced in the track rails between said tender and trailing 125 train, a current will flow in a local circuit comprising the two rails in multiple, the wheels and axle of the tender 221, conducting connections between the tender and train, shown as coupling bars 223 and 224, wheels and axles of the trailing 130 train 222 back to the track rails.

Various expedients may be employed to prevent such flow of current in the local dissipating circuit just mentioned, for instance, the coupling bar 223 may be insulated from the tender and other 135 devices connecting the tender and trailing train, such as air-hose, steam-hose and the like, may be insulated likewise. The flow of such current, however, is preferably prevented by inducing a voltage into the coupling bar and other connections, which is substantially equal to the voltage induced in the track rails and in the same direction with respect to said track. Means for inducing such a voltage in the coupling bar 223 has been provided by mounting a closed laminated core 225 on the rear end of the tender 221, through which the coupler or drawbar 223 and other devices connecting the tender with the trailing train pass. On this core 225 is provided 145 a coil 226 which is connected in series with the 150

wire 100, therefore causing the current flowing through the coils of the inducing elements IE to flow through the coil 226 of the inducing transformer IT formed by this coil and the core 225. 5 The several devices are designed with relation to each other, so that the voltage induced in the track rails and the voltage induced in the coupler bar 223 are substantially the same. This construction, therefore, induces a voltage in the train 10 and in the track, so to speak, which produces a flow of current in the winding 17 of the transformer P at the exit end of the block I (see Fig. 3), assuming the vehicle so equipped to be moving in this block. The other winding 15 of this 15 transformer P will in turn cause a current to flow in the loop circuit ahead of the train, which current will be detected by the receiving elements RE in front of the locomotive, as conventionally illustrated by the wheels and axle 228. The manner in which the train may be controlled by the 20 current thus picked up from the loop circuit is obvious from the illustration and description of Fig. 3.

It should, however, be noted that the receiving 25 elements RE and the inducing elements IE are used for inducing purposes when the train is moving in a direction to place them at the rear end, and are used for receiving purposes when the vehicle is moving in a direction to place 30 them on the front end thereof. Further, when one of these sets of devices is used for inducing purposes, the inducing elements IE are connected in multiple with each other and in series with the inducing transformer IT, in a manner so that 35 a voltage is induced in the two rails in multiple and coupling bar in the same direction; and when connected for receiving purposes are connected in series so as to detect current flowing in the opposite direction in the two track rails, 40 leaving the inducing transformer IT associated therewith in an open circuit. The inducing transformer IT, located in front of the locomotive 228, is positioned so that the auxiliary coupler bar 227 passes through the core 225 of this 45 transformer.

If a train control system, such as illustrated 50 in Fig. 3, is desired, with the exception that it is preferred to induce current into the two rails in multiple, and in turn detect signaling and 55 control current from the loop circuit ahead of the train, this may be accomplished by substituting the inducing and receiving devices shown in Fig. 5, bearing of course in mind that the several devices must be designed with respect to each other for such use.

The inducing and receiving devices illustrated 60 in Fig. 6 function substantially the same as those illustrated in Fig. 5, that is, they induce voltages in the same direction in the two rails in multiple, and detect the flow and character of the current flowing in the loop circuit ahead of the train. The principal departure consists in providing for the inducing element a single U-shaped core similar to the receiving elements RE illustrated in Fig. 2, only that this inducing element 65 is sufficiently long to bridge both of the track rails, and is located in front of the locomotive or vehicle, as represented by the axle and wheels 228. This inducing element IE comprises a long 70 U-shaped laminated core 229 provided with a winding 230, preferably extending entirely along the back yoke and along the legs formed by this core. In this form of the invention, no local dissipating circuit is present, since the inducing 75 is accomplished ahead of all the axles; and

therefore the additional inducing transformer IT illustrated in Fig. 5 is unnecessary.

In Fig. 7 has been illustrated still another form of inducing and receiving apparatus. In this embodiment of the invention, both the inducing 80 winding and the receiving winding are mounted on the same core structure. This combined inducing and receiving element IRE comprises a back yoke 232 having three downwardly extending legs 233, 234 and 235, respectively. These 85 legs terminate in suitable pole pieces 236. The outside legs 233 and 235 and the back yoke 232 are provided with an inducing winding 237, which, if energized by alternating current, causes an alternating flux to link about both rails of 90 the trackway, thereby inducing voltage in both rails in the same direction. The voltage induced in the track rails in this manner may be utilized to energize a transformer at the exit end of the 95 block which will induce a current in the loop circuit ahead of the train, that is, will induce a current flowing toward the train in one rail through the axles of the train back through the other rail to the transformer just mentioned. The alternating current induced in the loop circuit 100 in this manner will cause an alternating magnetism to be set up in the inducing and receiving element IRE through the following partial magnetic circuits, one of which comprises the leg 234, one half of the back yoke 232 and 105 the outside leg 235, and another partial magnetic circuit comprising the middle leg 234, the other half of the back yoke 232 and the other outside leg 233. It is thus seen that substantially all of the magnetism flowing in the inducing and 110 receiving element IRE, due to the current flowing in the loop circuit, passes through the middle leg 234, whereas very little flux passes through this middle leg due to the current flowing in the winding 237. It is, therefore, apparent that the 115 voltage induced in the coil 238 surrounding the middle leg 234 may be amplified and transmitted to the secondary winding of the relay R heretofore described to control the train in a manner 120 dependent on traffic conditions in advance.

If it is desired to use the inducing and receiving 125 devices illustrated in Figs. 6 and 7 for double end equipment, that is, so that either end of the vehicle equipped may run ahead, duplicate inducing and receiving devices, such as shown, may be mounted on the opposite ends of the vehicle. To throw either of these devices into service, depending on the direction of movement, a four-pole double-throw switch may be provided, of 130 which the blades are connected to the inducing bus IB and the receiving bus RB illustrated in Fig. 3, respectively, and of which the stationary clips on one side of the switch are connected to the proper lead-in wires of one of said devices, and of which the stationary clips on the other side of the switch are connected to the other of 135 said devices; whereby if the switch is thrown one way, one of these devices will be cut into service, and if the switch is thrown the other way, the other device will be cut in.

Structure of Fig. 8.—In Fig. 8 has been illustrated still another modified form embodying the present invention in which two-condition continuous control may be obtained without providing any additional line wires. In this form of the invention, the coils 8 of the inducing or generating elements IE are located in front of the locomotive and are connected in series in a manner to induce a voltage in one direction in one of the rails and in the other direction in the other of

said rails, thus causing a current to flow in the loop circuit ahead of the train either through an inductive reactance 240 or an ohmic resistance 241, depending on traffic conditions in the block 5 ahead.

While various devices may be employed for detecting or receiving currents responsive to current flowing in the loop circuit ahead of the train as already described in connection with previous 10 forms of this invention, still another means for this purpose is used in Fig. 8. It has been found in practice that a large percentage of the current flowing in the track circuit shunted by a train flows through the wheels and axles of the first 15 truck of the train. It has, therefore, been proposed to provide means for detecting the flow of current through one or more of the axles of the first truck of the train by the well-known transformer principle, this principle being especially 20 well adapted for this purpose. This axle transformer AT has been illustrated by a core 242 constructed of a high grade of laminated transformer iron and provided with a secondary coil 243, the primary winding of the transformer consisting 25 of a single turn which comprises the car axle itself. The presence of the current in the loop circuit and its phase relation with respect to the voltage generated by the polyphase alternating current generator 244 is preferably ascertained 30 by the employment of a phase responsive relay PR, which will precisely indicate the phase relation between two alternating currents. Such a phase responsive relay PR has been conventionally shown, and comprises a stator similar to that 35 of a polyphase induction motor and a rotor having a single or polyphase winding.

The phase responsive relay PR more specifically comprises a stator having a three-phase winding, as indicated by the coils 245, 246 and 247, this 40 stator winding being directly energized through the lead-in wires 248, 249 and 250 leading to the three terminals of the polyphase alternating current generator 244. Within the stator is pivotally mounted a rotor which is provided with a 45 single phase winding 251 to be connected to the source of alternating current voltage, the phase relation of which, with respect to that of the phase relation of the voltage impressed on the stator, is to be determined. This rotor winding 251 may surround an iron core, but if such an iron core is employed, the construction should be 50 such that practically no turning moment will be produced if the stator only is energized. This may be done by mounting a stationary core within 55 the stator about which the winding 251 is adapted to rotate. The circuit controller adapted to be actuated by this phase responsive device has been conventionally shown to illustrate how this 60 device may be constructed so as to maintain a circuit closed when a certain predetermined range of phase displacement exists between the voltage impressed on the rotor winding and the voltage across any one of the phases of the stator winding.

65 This circuit controller comprises a disc 254 fastened to the relay shaft 252. This shaft 252 and disc 254 are biased to a deenergized position by a hair-spring 253, this position being shown in dotted lines. The disc 254 is provided with a pin 258 adapted to engage the movable contact 256. With the relay energized to a position such as the position illustrated in the drawings, the movable contact 256 will be held in engagement 70 with the stationary contact 257 by a spring 255. The hair-spring 253 is, however, strong enough

to open the contacts 256-257 against the tension of the spring 255 when the phase relation of the currents is such as to allow the pin 258 to strike the movable contact 256.

If now the relay PR is energized by current 80 having a predetermined range of phase relation, the disc 254 will be brought to a position, such as the position indicated in the drawings, thereby allowing the spring 255 to bring the contact finger 256 against the stationary contact 257. If now the phase relation changes to move the disc toward the dotted position, nothing happens until the pin 258 strikes the contact finger 256 and urges it away from the stationary contact 257 against the tension of the spring 255. Consequently, if for any reason the phase responsive relay PR is deenergized, the hair-spring 253 will overcome the tension of the spring 255 to interrupt a circuit adapted to be completed through the movable contact finger 256 and stationary contact 257. In practice the movable 90 element of this relay is preferably well balanced, and is also preferably supported in a heavy spring supported casing, so that its operation will not be affected by jars and vibration. The circuit 95 for energizing the rotor winding 251 of the phase responsive relay PR may be traced as follows:—Beginning at the secondary winding 243 of the transformer AT, wire 259, inlet wire 32 through the amplifying device A, outlet wire 59, wire 260, 100 winding 251 of the relay PR, wires 261 and 55 back through the amplifying device A, wires 31 and 262 back to the secondary winding 243 of the transformer AT.

A condenser 263 connected in multiple with the 110 secondary winding 243 of the axle transformer AT, which is tuned to resonance with this winding 243 at the frequency at which the device is to be operated, is provided in order to improve the efficiency and operating characteristics of 115 the apparatus. A similar condenser 264, similarly adjusted with respect to the winding 251 of the phase responsive relay PR, is provided.

Operation of Fig. 8.—Let us assume that a railway vehicle equipped with the car apparatus illustrated in Fig. 8 is moving in a block, such as the block I, under normal clear traffic conditions, that is, with the portion ahead of the train in the block I as well as the block J unoccupied. Under this condition, the track relay 54 will be 125 energized, thereby including the inductive reactance 240 in the track circuit of the block I. The inducing or generating elements IE are connected across the terminals of the polyphase alternating current generator 244 through a circuit 130 which is obvious from the drawings. The alternating flux around the track rails, due to the exciting current flowing in the coils 8 of the inducing elements IE, will cause a current to flow in the loop circuit ahead of the train 135 which lags considerably behind the voltage producing it. This lag in the flow of the current in the loop circuit is mainly due to the inductive reactance 240, and is also partially due to the reactance of the track rails themselves.

Since a large percentage of the current flowing in this loop circuit passes through the axles of the front truck of the train, an alternating magnetic flux will be set up in the core 242 of the axle transformer AT, thereby producing an alternating current voltage in the secondary coil 243 thereof. This voltage is impressed on the amplifying device A, whereby it is amplified and transmitted to the rotor winding 251 of the phase responsive relay PR through the circuit heretofore traced.

- The flow of this current in the rotor winding acts on the rotating magnetic field produced by the stator winding to actuate the disc 254 against the action of the hair-spring 253 to a position dependent on the phase relation of this current to that of the voltage impressed on the stator windings, which may be assumed to be the position illustrated, thereby maintaining the movable contact finger against the stationary contact to complete a circuit through the train control device K, which is obvious from the drawings. The energization of this circuit will allow the train to proceed unrestricted by the automatic train control apparatus.
- Let us assume, now, that the block J is occupied by another train which will shunt the usual track circuit current of the block J through the wheels and axles of said train, thereby deenergizing the track relay 5¹, thus causing it to drop its make-before-break contact 265¹. During this dropping of the contact 265¹, the track circuit of the block I will not be momentarily interrupted, because the back contact will make the circuit through the ohmic resistance 241 before the front contact will break the track circuit through the inductive reactance 240. The track circuit of the block I has now been changed to a circuit which comprises to a large extent an ohmic resistance, because the inductive reactance 240 has been omitted. In practice the ohmic resistance of inductive reactance 240 is made substantially the same as the resistance 241, so that the direct current constants will be the same in each case. The alternating current now flowing in the loop circuit of the block I is much nearer in phase with the voltage producing it, or in other words, the current flowing is to a large extent ohmic or a power current. This current will be transformed, amplified, and transmitted to the rotor winding 251 of the relay PR, in the same manner as heretofore explained in connection with the reactive current produced in a clear block. With this current flowing in the rotor winding 251 of the relay PR, the disc 254 will assume a position which, as before, is dependent on the phase relation of this current to that of the currents flowing in the stator winding, and is substantially independent of the value of this current itself, for instance, such as the dotted position illustrated, thereby causing the pin 258 to strike the contact finger 256 and open the circuit through the train control device K.
- The deenergization of the train control device K will enforce a speed restriction or other control dependent on the design and construction of this device. This device is preferably of a character to compel a reduction in speed until a final low speed limit is reached, which will be enforced until a clear block is entered, or until the block in which the restricted train is running clears up.
- Assuming, now, that a train equipped with the apparatus in question is entering the block I under danger traffic conditions, that is, when the block is occupied by another train. Under this condition, the loop circuit ahead of the train is also resistive to a large extent, regardless of whether the track relay 5¹ at the entrance of the block J is energized or deenergized, because this loop circuit is completed through the wheels and axles of said another train ahead of the train in question. The current transformed, amplified, and transmitted to the rotor winding 251 of the phase responsive relay PR under these conditions will be substantially the same as under caution traffic conditions, as explained in the preceding paragraph; and since in both instances the loop

circuit is only slightly inductive, the train will be restricted in its movement in the same manner as under caution traffic conditions.

Description of Fig. 9.—In practice it has been found that many of the important railroads have a large portion of their roadway provided with direct current block signaling equipment including direct current track circuits, but that at local points in such sections a few blocks of alternating current track circuits are often employed. This is usually because local conditions make the use of direct current circuits unreliable on account of the presence of stray direct current flowing in the track rails. Such currents are usually due to bad bonding on other parallel railroads using direct current for traction purposes. Further, it is also found that some of the important railway systems are partially electrified, and are using direct current for propulsion purposes which also requires the use of alternating current track circuits for governing wayside signals, and the like. In order to facilitate train control on railroads of this kind, it has been proposed to superimpose suitable trackway devices and circuits, on both direct current and alternating track circuit territory, which, although different in character, will adapt them for the track circuit with which they are used without interference, and will affect suitable car-carried train control apparatus in accordance with traffic conditions ahead.

It is proposed in the present embodiment to transform relatively high frequency alternating current into the loop circuit of a direct current track circuit by connecting the secondary of a transformer in series with the usual track battery; and to transform similar high frequency alternating current into an alternating current track circuit by connecting a transformer having a current limiting device in series therewith which is tuned to resonance at said relatively high frequency in multiple with the usual track circuit transformer. This arrangement of connections in alternating current track circuits will permit such high frequency current to pass through said current limiting device, but will not let an alternating current of commercial frequency pass therethrough to any appreciable extent; and on the other hand, the high frequency alternating current will not be able to pass through the secondary winding of the track-circuit transformer to any appreciable extent, because of the high value of self-induction of this secondary at such a high frequency.

One of each of said types of trackway circuits has been illustrated in Fig. 9, one of which is adapted to be superimposed on an alternating current block signal system, such as the blocks H and I shown, and the other to be superimposed on a direct current block signal system, similar to the block I shown in Fig. 3, as shown by the blocks J and K. These trackway circuits are so constructed that a vehicle equipped with the inducing and receiving apparatus, such as illustrated in Figs. 3, 5, 6 and 7, may induce and also detect current independently of the direct current or alternating current track circuit current flowing, and control the train according to the relative instantaneous polarity of the current detected with respect to the instantaneous current supplied by the alternating current generator carried by the railway vehicle. This is because the alternating current detected must be of the same frequency and of a certain phase relation within certain limits to that of the cur-

rent impressed on the other phase of the relay R as illustrated. The blocks H and I are of a type employing an alternating current in their track circuits, as illustrated by the alternating current 5 track relay 281 at the entrance of block I, and a trackway transformer TT supplied from an alternating current transmission line 282 provided at the exit end of said block.

In the block I has been shown an inducing circuit, which may be traced as follows:—Beginning 10 at the track rails 1 and 2 in multiple, to the middle point of the balancing resistance BR at the entrance of the block, line wire 266, stationary contact 267¹, movable contact 268¹, wire 269, 15 primary winding 270 of the transformer P, wire 271, movable contact 272¹, stationary contact 273¹, wire 274 to the middle point of the balancing resistance BR located at the exit end of the block I, back to the track rails 1 and 2.

20 The induction of an electro-motive-force in this inducing circuit will cause a current to flow in the loop circuit including the secondary of said transformer P, which circuit may be traced as follows:—Beginning at the secondary winding 275 of the transformer P, wire 276, condenser 277 in multiple with the adjustable inductive reactance 278, wire 279, track rail 1, through the axles of the train occupying the block I at this time, through the rail 2, wire 280 back to the 30 secondary winding of the transformer P.

Under clear traffic conditions of the block I, a train equipped with the apparatus heretofore described, and provided with inducing and receiving elements, such as shown in Figs. 5, 6 and 35 7, will induce a current in the inducing circuit which will be transformed by the transformer P in the loop circuit ahead of the train. The voltage impressed across the track rails 1 and 2 of the loop circuit will permit very little, if any, 40 current to flow in the local circuit completed by the usual trackway transformer TT, because the self-induction of a trackway transformer of this type which is designed for commercial frequencies has sufficient self-induction to prevent the 45 flow of alternating current of a relatively high frequency therethrough. On the other hand, the secondary winding 275 of the transformer P will permit very little, if any, current from the trackway transformer TT to flow therethrough, 50 because it has connected in series therewith a current limiting device, comprising a condenser 277 shunted by an adjustable inductive reactance 278 which has been tuned to resonance to the 55 relatively high frequency by the generator carried by the railway vehicle. Since a current of high frequency may be induced in the loop circuit of an alternating current trackway circuit as illustrated and described, it is apparent that 60 automatic train control may be carried out in the same general way as heretofore shown and described in connection with direct current track circuit territory, therefore facilitating train control in a composite system where both direct current and alternating current track circuits are 65 employed.

In the block J of Fig. 9 has been illustrated 70 trackway equipment for facilitating automatic train control in direct current track circuit territory, which equipment functions the same as that described in connection with Fig. 3, and therefore need not be specifically described. The 75 parts and circuits at the junction of blocks J and K of Fig. 9 have as a matter of convenience been given the same reference characters as the corresponding parts and circuits at the junction of

blocks I and J of Fig. 3, except that the exponents of the reference characters are one number higher.

While different specific detail arrangements and constructions of devices and circuits have 80 been illustrated and described in order to explain the characteristic features of the invention, it should be understood that the invention is not limited solely to these specific organizations, and that certain characteristic means and functions used in one embodiment are adaptable and are intended to be used in connection with other embodiments where it is desired to take advantage of the additional features provided thereby. Also, in order to avoid unnecessary 90 complication in the description and explanation, many things concerning the detailed design and manner of practicing the invention have not been described in full detail, it being considered that one skilled in the art will adapt and modify 95 the size and shape of cores, windings, frequencies, etc., as may be desirable to best meet the individual conditions under which an installation is to be made.

Regarding the frequency, as previously stated, 100 it is considered preferable in most instances to employ a relatively high frequency, subject to the limits imposed by the reactance of the track rails themselves. Furthermore, in order to avoid any possible interference between the signaling 105 current produced on one train or vehicle with the receiving equipment by another train or vehicle and perhaps under unfavorable conditions produce an improper control between trains, it is contemplated that the inducing and 110 receiving equipment of each train will be designed or adjusted for one particular frequency distinctive from the signaling frequency of all other trains. By carefully tuning the receiving equipment in the manner well-known in the art, 115 it can be assured that this receiving means will not be influenced by a signaling current other than that produced on that train itself. Similarly, while one specific arrangement of amplifying means has been shown and described as 120 typical of that employed in connection with this invention, it should be understood that this is also susceptible of considerable adaptation and modification in practice. In short, the various 125 elements of the different specific forms of systems shown, such as the inducing elements and receiving elements, amplifying means, change-over switches and devices and the like, are capable of re-organization or re-arrangement to produce the particular character of system desired. Consequently, any particular combination 130 or arrangement of parts, or electrical structures, should not be excluded from the scope of this invention merely because they have not been individually shown or described.

135 Means have been provided by this invention for facilitating automatic train control which is continuous in its functions, thereby apprising the engineer and controlling the train automatically the moment a dangerous traffic condition is present, and further advises the engineer and removes the restriction enforced due to danger traffic conditions the moment such danger traffic conditions are removed. Further, such an automatic train control system has been provided 140 which will function equally as well in direct current track circuit territory as it does in alternating current track circuit territory, and permits either end of the vehicle to run ahead without adding duplicate equipment for this purpose. 145

A train control system has thus been provided which does not require the transmission of current along the trackway from a source of energy on the ground, which current is unreliable and often fails along a long stretch of track, thereby removing all automatic protection which it otherwise affords. In the present system, if the source of energy should fail, it affects the particular train upon which the breakdown occurs; and on the other hand, if a line circuit or other track equipment cooperating with this train control system should fail, only that particular block in which it is located is affected. It is thus seen that in the event of a breakdown, whether on the car-carried apparatus or the trackway equipment, it is local in character, that is, it affects either a single train or a single block; whereas if alternating current transmitted by a long transmission line is relied upon, a large section of the system is very apt to be disabled at one time.

Having thus shown and described several embodiments of the present invention, it should be understood that many other arrangements of devices may be employed which have not been specifically illustrated, for instance, each of the modified forms of the inducing and receiving elements illustrated may by proper design be employed in any one of the systems shown and described; and we desire to have it understood that various obvious changes and adaptations may be made without departing from the spirit and scope of this invention.

What we claim is:—

- 35 1. In an automatic train control system of the type in which a control influence of the proper character must be present to allow the train to proceed unrestricted, of means carried by the train for producing a flow of current in the usual track rails ahead of the train at the particular time, said current flowing from a point at a distance ahead of the train through the track rails in opposite directions, and means on the train governed by said current for controlling the movement of said train.
- 40 2. In an automatic train control system of the type in which a control influence of the proper character must be present to allow the train to proceed unrestricted, of means carried by the train for producing a flow of current in the usual track circuit occupied by the train at the particular time, and means on the train jointly governed by currents so produced in said track circuit and said first mentioned means directly for controlling the movement of said train.
- 45 3. In an automatic train control system of the type in which a continuous control influence is necessary to allow the train to proceed unrestricted, of car-carried means for inducing an alternating current in a circuit including the track rails ahead of the train, said current flowing from a point at a distance ahead of the train back to the train through the track rails in opposite directions, and a train control device on the car maintained inactive by the current in said circuit.
- 50 4. In a train control system for railroads having tracks divided into blocks, a transformer having its secondary connected across the track rails at the exit end of each block, and car-carried means including a source of current on the car and a circuit on the trackway for supplying alternating current from said car-carried source to the primary of the transformer of a given

block at all points in the travel of the car through that block.

5. In an automatic train control system of the continuous inductive type, the combination of car-carried alternating current apparatus for inducing alternating current in a circuit comprising the two track rails in multiple and a return wire, means whereby the current in said circuit produces an alternating current in the usual track rails ahead of the train flowing in opposite directions therein under clear traffic conditions, and means for maintaining a train control device inactive only so long as there is current of a predetermined character flowing in one direction in one rail and in the other direction in the other rail directly in front of the train.

6. In an automatic train control system in which a continuous influence of a predetermined character must be transmitted from the trackway to a suitable car-carried apparatus to allow the train to proceed without restriction, of means partly on the vehicle and partly along the trackway for transmitting alternating current to a translating device located along the trackway, traffic controlled means for energizing a track circuit including both of the running rails by said translating device in a plurality of different ways, and car-carried train control means maintained inactive by current of a predetermined character in said track circuit.

7. Influence communicating means for train control systems comprising, car-carried means for inducing an alternating current in a circuit including the two rails in multiple, and means for detecting a corresponding current in a circuit including the two rails in series.

8. In a train control system of the continuous inductive control type and adaptable for controlling trains on railroads having territory equipped with direct current track circuits and other territory equipped with alternating current track circuits, the combination of means on a car for inductively detecting the flow of alternating current in opposite directions in the track rails directly ahead of the car such as flows in the alternating current track circuits, and means for producing a similar alternating current from a car-carried source in the track rails of each block having a direct current track circuit.

9. A train control system of the continuous inductive type comprising, receiving coils at different points on a locomotive for detecting the flow of alternating current in the track rails in opposite directions and in the same direction respectively, electro-responsive means on the locomotive having two input circuits, and automatic means having its operation dependent upon the direction of rotation of the locomotive wheels for interchanging the connections between said receiving coils and said input circuits as the locomotive changes its direction of movement.

10. In a train control system comprising, means for detecting the flow of alternating current in the same direction in both track rails at one end of a locomotive equipment, means for detecting the flow of alternating current in opposite directions in the two rails at the opposite end of said equipment, train control means governed by said currents, and automatic means for interchanging said two detecting means with respect to the circuits of the car equipment when the direction of movement of the vehicle changes.

11. In a train control system comprising, means for detecting the flow of alternating current in the same direction in both track rails at one end

- of a locomotive equipment, means for detecting the flow of alternating current in opposite directions in the two rails at the opposite end of said equipment, train control means governed by said currents, and means for electrically interchanging said two detecting means. 80
12. An automatic train control system comprising, automatic train control means, means for energizing said automatic means to maintain it inactive, and means for removing the restriction of said automatic means when deenergized which requires continuous movement by the operator to maintain it effective. 85
13. A device for reducing the restriction imposed by an automatic train control device comprising, apparatus adapted to be operated by the engineer which will remove such restriction when and only when said device is maintained in motion. 90
- 20 14. Influence communicating devices for automatic train control systems comprising, a car-carried alternating current device for inducing alternating current in a track circuit, a train control device maintained inactive by the current in said circuit if said current has a proper and predetermined phase relation with the voltage of said alternating current device, and traffic controlled means on the trackway for changing said phase relation. 95
- 30 15. In an automatic train control system for railroads having tracks divided into blocks each having the usual track circuit, the combination with a circuit on the trackway associated with each block, car-carried devices including a source of alternating current for inducing alternating current in said circuit on the trackway, automatic means controlled by the track circuit of the block next in advance for supplying current from said trackway circuit across the track rails at the exit end of each block, and car-carried means inductively influenced by the current in the track rails directly ahead of the car which flows in opposite directions, said car-carried means having a tendency to assume its active condition and being maintained inactive only so long as said current influencing it is flowing. 100
- 40 16. In an automatic train control system of the type in which a continuous influence of a predetermined character must be transmitted from the trackway to suitable car-carried apparatus to allow the train to proceed without restriction, of car-carried means including a source of alternating current for energizing the usual track circuit including the track rails in advance of a train in question with alternating current flowing in opposite direction in said track rails, and other car-carried means for detecting by induction the presence and character of the current produced by said source and flowing in said track circuit. 105
- 50 17. In an automatic train control system for railroads provided with blocks each having a track circuit, two circuits on the trackway for each block and each including in part the track rails of that block, means controlled by the track circuit of each block for controlling the electrical connection between said two circuits of the block next in the rear, car-carried means including a source of alternating current for inducing current in one of said trackway circuits at all points in the travel of the car through the corresponding block, and other car-carried means for inductively detecting the flow of current in the other of said trackway circuits. 110
- 60 18. In a train control system for railroads, the combination with a section of track, a trackway circuit for supplying signaling current to the track rails of said section at the exit end thereof, said signaling current flowing in opposite directions in the track rails, means on the car for detecting the flow of signaling current in the track rails directly in front of the car, and means including a car-carried source of electrical energy for inducing signaling current in said trackway circuit at all points in the travel of the car through said track section. 115
- 70 19. In a train control system, the combination with a section of track, a transformer having one winding connected across the track rails of said section at the exit end thereof, a circuit along the trackway for supplying current to the other winding of said transformer, and means on the car for inducing current in said circuit from a car-carried source of electrical energy at all points in the travel of the car through said section. 120
- 80 20. The method of communicating control influences for train control systems from the trackway to moving trains in accordance with traffic conditions which consists, in producing in the track rails ahead of a train a signaling current derived from a source on that train, controlling this signaling current in accordance with the extent of unoccupied track in advance of said train, transmitting said signaling current so controlled along a path adjacent to said train, and finally detecting on said train by induction through an intervening air gap the existence of said signaling current. 125
- 90 21. The method of continuously determining the extent of unoccupied track in front of a train for the purpose of governing cab signal or train control mechanism upon that train in accordance with traffic conditions in advance thereof which consists, in producing in a trackway circuit by induction a signaling current derived wholly from a source of energy on the train, controlling said signaling current in accordance with the extent of unoccupied track in advance of said train, and transmitting said signaling current so controlled by induction to said train and there detecting its existence and character. 130
- 100 22. The method of continuously communicating control influences to a railway train dependent upon the presence or absence of another train on the track rails in advance thereof which consists, in producing in said track rails by induction from a source of energy on the train an alternating signaling current flowing in opposite directions at any instant in the track rails so as to be shunted by the wheels and axles of another train ahead of said train, and detecting by induction through an intervening air gap the flow of signaling current in the track rails adjacent to said train. 135
- 110 23. The method of continuous control for cab signal and train control systems which consists, in inducing from a car-carried source of energy an alternating signaling current which flows in a loop circuit from a distant point ahead of the car in opposite directions through the track rails, controlling the signaling current in said loop circuit in accordance with the presence or absence of other trains ahead, and finally detecting on said car the existence of said signaling current after being so controlled. 140
- 120 24. The method of controlling trains on railroads which consists, in ascertaining the condition of the track in advance of a train by inducing in the track rails an alternating current, mod- 145
- 130
- 140
- 150

- ifying the phase relation of said current in accordance with the presence or absence of other trains ahead, and then detecting on said train such phase relation.
- 5 25. The method of continuous control for train control systems which consists, in providing a loop circuit and a receiving circuit along the trackway one including the track rails in series, inducing from a car-carried source an alternating signaling current in the loop circuit, controlling the electrical connection between the loop circuit and the receiving circuit in accordance with traffic conditions in advance, and finally detecting the existence of signaling current in the receiving circuit. 80
- 10 26. The method of continuous inductive train control which consists, in communicating between the trackway and a moving train by electro-magnetic induction by utilizing current flowing in the track rails which current is wholly derived from a source of current on the car itself, changing the polarity of the current in accordance with traffic conditions ahead and detecting inductively the modified current on that same car. 85
- 15 27. The method of continuously controlling train movements in accordance with traffic conditions along the trackway in advance of a train which consists, in supplying a signaling current from a source of energy wholly on the train to a trackway circuit including the track rails and a controllable translating device, and continuously inductively detecting on the train said current as controlled by the translating device. 90
- 20 28. The method of continuously communicating control influences to moving trains during their progress through blocks having normally closed track circuits which consists, in inducing in the track rails of each block an alternating signaling current, controlling that signaling current in accordance with the presence or absence of another train on the track circuit next in advance, and detecting on the following train by magnetic induction through an air gap the signaling current so controlled. 95
- 25 29. The method of continuous control for train control systems which consists, in producing in the track rails in advance of a car an alternating current derived wholly from a source of alternating current on said car, controlling the phase relation of said signaling current with respect to the producing source in accordance with the presence or absence of other trains ahead, and finally automatically determining on said car the phase relation of said current so controlled. 100
- 30 30. The method of train control which consists, in continuously maintaining train control means on a car which has a tendency to assume its active condition in the inactive condition so long as a predetermined extent of track in advance of the car is unoccupied, by inducing in a loop circuit and a receiving circuit along the track an alternating signaling current derived wholly from a source of energy on the car, one 105 of said trackway circuits including the track rails in series for a predetermined distance in advance of the car so that the flow of signaling current in that circuit is affected by the shunting action of the wheels and axles of another train, controlling the electrical connection between said circuits in accordance with the presence or absence of another train still further in advance, and inductively detecting on said car the existence and character of the signaling current in the 110 trackway receiving circuit. 115
- 35 31. The method of train control for railroads having some portions thereof equipped with an alternating current supply and other portions having no trackway source of alternating current, which consists in supplying to the track rails an alternating signaling current derived from the trackway source where available and from a car-carried source where not available, and inductively detecting such signaling current. 120
- 40 32. The method of train control for railroads in which portions of the track have an alternating current in the track rails controllable by the shunting action of wheels and axles of the train and in which other portions of the track have a direct current in the track rails which consists, in supplying throughout all portions of the railroad an alternating signaling current in the track rails ahead of a car, maintaining or interrupting that signaling current dependent upon the presence or absence of other trains ahead, and detecting by induction the existence and character of said signaling current after being so controlled. 125
- 45 33. The method of train control which consists, in governing an electro-responsive device on a car in accordance with the existence and phase relation of a current on the track rails adjacent to the car which current is produced in the track rails inductively from a source wholly on the car and has its phase relation varied by the presence of other trains ahead. 130
- 50 34. In a train control system, the combination of biased electro-responsive means on a car, means inductively responsive to the flow of alternating current in the track rails on which the car is running for governing said electro-responsive means and maintaining it energized under clear traffic conditions ahead by such current, and means for producing in said track rails an alternating signaling current derived wholly from a source of energy on said car and automatically controlled in accordance with the presence or absence of other trains ahead. 135
- 55 35. In a train control system, a trackway loop circuit and a receiving circuit one including a predetermined length of the track rails in series, car-carried means including a source of alternating current for inducing in the loop circuit a signaling current and for detecting the flow of such signaling current in said receiving circuit, and means responsive to the presence or absence of trains for controlling the transmitting connection between said loop circuit and said receiving circuit. 140
- 60 36. A continuous control system for railroads having track divided into blocks each equipped with a normally closed track circuit, a wayside circuit for each block including the track rails thereof, means controlling the flow of current in said wayside circuit by the track circuit of the block next in advance, car-carried means for producing in the wayside circuit a signaling current, and car-carried means inductively controlled by the current in the wayside circuits. 145
- 65 37. In a train control system for railroads having tracks divided into blocks each equipped with a normally closed circuit, a wayside circuit for each block including the track rails thereof in series, another wayside circuit for each block including the track rails in multiple, means controlled by the track circuit of the block next in advance for governing the transmission connection between said two wayside circuits, means on a car for inducing in one of the wayside circuits an alternating signaling current, and means 150

on the same car inductively influenced by the signaling current in the other wayside circuit.

38. In an automatic train control system, the combination with two coupled cars, means carried over the track rails between said cars for inducing alternating current in said track rails, and means for preventing the flow of said current from one car to the other.

39. In a train control system, means for continuously communicating a control influence from the trackway to a moving train at all points in its travel dependent upon traffic conditions in advance comprising, a source of relatively high frequency on a car, means energized from said source for inducing in a wayside circuit a signaling current, a signaling circuit including the track rails in multiple, traffic controlled means inductively connecting at times said wayside circuit to said signaling circuit, and electro-responsive means on the car energized in part from said source and governed by current derived from said signaling circuit.

40. In a train control system; means for continuously communicating a control influence from the trackway to a moving train at all points in its travel dependent upon traffic conditions in advance comprising, inducing and receiving equipments on a car energized wholly from a source of electrical energy on the car; and traffic controlled trackway means cooperating with said equipments to provide a transmitting connection of one character from the inducing equipment to the receiving equipment under safe traffic conditions, a transmitting connection of another character under caution traffic conditions, and shunting said inducing equipment from said transmitting equipment under danger traffic conditions.

41. In a train control system, means for continuously communicating a control influence from the trackway to a moving train at all points in its travel dependent upon traffic conditions in advance comprising, a car-carried source of alternating current, means on the car energized from said source for inducing current in a trackway circuit, and means on the car for detecting and amplifying the signaling current along the trackway.

42. In combination, a railway track divided into sections, means for supplying the rails of each section with line current throughout the length of the section regardless of traffic conditions in advance and also with track circuit current, the relative polarities of which currents are normal or reverse depending on traffic conditions in advance of the section, a vehicle carried relay controlled by said currents in the track rails and responsive to reversals of relative polarity thereof, a valve on the vehicle arranged when open to apply the brakes, and means for keeping said valve closed when said relay is energized in the normal direction regardless of the speed of the vehicle but for permitting said valve to open when the relay is energized in the reverse direction or is de-energized regardless of the speed of the vehicle.

43. In combination, a section of railway track, means for supplying said section throughout its length with track circuit current and with line current the relative polarity of which currents is normal when traffic conditions in advance are safe and the relative polarity of which currents is reversed when traffic conditions in advance are dangerous, and train carried governing means arranged to apply the brakes regardless of the

speed of the train when the trackway currents are of reverse relative polarity but not when such currents are of normal relative polarity.

44. In combination, a railway track divided into sections, means for supplying each section throughout its length with line current regardless of traffic conditions in advance and with track circuit current, the relative polarities of which currents are normal or reverse depending on traffic conditions in advance of the section, and train carried governing mechanism controlled by said currents.

45. In combination, a railway track divided into sections, means for supplying each section throughout its length with line current regardless of traffic conditions in advance and with track circuit current, the relative polarities of which currents are normal or reverse depending on traffic conditions in advance of the section, a train carried relay controlled by said currents and responsive to reversals of relative polarity thereof, and governing means on the train controlled by said relay.

46. Railway vehicle carried apparatus comprising front and rear receiving coils mounted in inductive relation to the track rails, and a circuit controller effective when in normal position to close a track receiving circuit including a front coil for one rail and a front coil for the other rail connected in opposition and to close a local receiving circuit including a rear coil for one rail and a rear coil for the other rail connected in series, said circuit controller when in reverse position being effective to close a track receiving circuit including a rear coil for one rail and a rear coil for the other rail connected in opposition and to also close a local receiving circuit including a front coil for one rail and a front coil for the other rail connected in series.

47. Railway vehicle carried apparatus comprising front and rear receiving coils mounted in inductive relation to the track rails, a normal track receiving circuit including a front coil for one rail and a front coil for the other rail connected in opposition, a normal local receiving circuit including a rear coil for one rail and a rear coil for the other rail connected in series, a reverse track receiving circuit including a rear coil for one rail and a rear coil for the other rail connected in opposition, a reverse local receiving circuit including a front coil for one rail and a front coil for the other rail connected in series, and circuit controlling means effective when in normal position to close said normal track receiving circuit and said normal local receiving circuit, said circuit controlling means being effective when in reverse position to close said reverse track receiving circuit and said reverse local receiving circuit.

48. In an automatic train control system, the combination of trackway means for causing alternating currents supplied from a transmission line to flow along the trackway in two distinctive circuits, one circuit of which includes the two track rails ahead of the car in series and the other of which includes the two track rails under the car in multiple, car-carried apparatus including two pairs of inductive influence receiving coils, one pair of which is located in front of the first axle of the car and connected to cumulatively detect currents flowing in opposite directions in the rails and the other pair of which is located behind the last axle of the car and connected to cumulatively detect currents flowing in the same direction in the two rails, and

- means effective to make the necessary changes in connections to cause said pairs of coils to detect such currents when the car is turned end for end and is moved along the track in the 5 same direction.
49. Railway traffic controlling apparatus comprising automatic mechanism carried on a train and operating under unsafe traffic conditions to apply the brakes, and means located on the train 10 for preventing an automatic brake application if the speed does not exceed a given value and if and only if the engineer takes suitable continuous action as long as the train proceeds under unsafe traffic conditions.
- 15 50. Railway traffic controlling apparatus comprising automatic mechanism carried on a train and effective continuously while the train is traveling under unsafe traffic conditions to apply the brakes, a circuit controller on the train 20 biased to the open position and requiring continuous manual action to keep it closed, and means controlled by said circuit controller for preventing an automatic brake application if and only if the circuit controller is kept closed continuously while the train is traveling under 25 unsafe traffic conditions.
- 30 51. Railway traffic controlling apparatus comprising automatic mechanism carried on a train and operating under unsafe traffic conditions to apply the brakes, a circuit controller on the train 35 biased to the open position and requiring continuous manual action to keep it closed, and means for preventing a brake application by said automatic mechanism if the speed is below a given value and if and only if said circuit controller is kept closed continuously while the train is traveling under unsafe traffic conditions.
- 40 52. In combination, a train carried relay controlled from the trackway and arranged to be energized or de-energized according as traffic 45 conditions in advance are safe or unsafe, a brake controlling magnet controlled by said relay and energized when said relay is energized, a circuit controller on the train biased to the open position 50 and requiring continuous manual action to keep it closed, and a circuit for said magnet controlled by said circuit controller and by a back contact of said relay and capable of keeping the magnet energized if and only if the circuit controller is continuously held closed by manual operation as long as the relay is de-energized.
- 55 53. Railway traffic controlling apparatus comprising means for supplying train governing current to the track rails under safe traffic conditions in advance and for discontinuing the supply of such current under unsafe traffic conditions in advance, automatic train carried mechanism controlled by said train governing current for applying the brakes in the absence of said current, and means located on the train for preventing operation of said automatic mechanism in the absence of said train governing current if and only if the engineer takes suitable continuous action.
- 60 54. Railway signaling means comprising a normally energized electro-magnet carried by the vehicle, a magnet in the trackway, a resistance element connected in circuit with said magnet, means for connecting and disconnecting said resistance in circuit with said magnet in accordance with traffic conditions ahead of the vehicle to control the phase angle of the current flowing in said magnet, and means on the vehicle controlled by said current and its phase angle.
- 65 70 75 55. In combination with the rails of a railway track and a vehicle, traveling thereon, car-carried means for causing flow of current in a track circuit including the track rails ahead of the vehicle, means for inserting an impedance in said track circuit under certain traffic conditions ahead, to change the phase angle of the current flowing and means on the vehicle responsive to said current and its phase angle.
- 80 56. In combination, a railway track comprising sections, means for supplying line current to the rails of a section throughout the length of the section regardless of traffic conditions in advance of the section, means for supplying the rails of a section with track circuit current of normal or reverse relative polarity according to traffic conditions in advance of the section, a vehicle carried relay controlled by said track rail currents and responsive to reversals of relative polarity of the track circuit current, and governing means on the vehicle controlled by said relay.
- 85 90 95 57. In combination, a railway track comprising sections, means for supplying line current to the rails of a section throughout the length of the section regardless of traffic conditions in advance of the section, means for supplying the rails of a section with track circuit current of normal or reverse relative polarity according to traffic conditions in advance of the section, and train carried governing means controlled by said track currents and responsive to reversals of the relative 100 polarity thereof.
- 100 105 110 115 58. In a train control system, a wayside system comprising a succession of block section circuits each including the track rails, means on a vehicle for transmitting energy into said circuits successively as the train proceeds, means in said circuits, subject to traffic control, for continuously sending energy back to said vehicle, and means on said vehicle for selectively receiving said returned energy continuously to the exclusion of 115 the transmitted energy and for operating a signal indication thereby.
- 120 125 130 135 59. The system for giving on a train an indication of traffic conditions ahead which comprises means upon the train for supplying electric energy to a wayside circuit which includes a wayside inductor, means in said wayside circuit for receiving said energy and for so retransmitting it back over the same wayside inductor to the train as to enable it to be received on the train 125 independently of the current from the original source on the train, and means in the wayside circuit for controlling the return transmission in accordance with traffic conditions ahead.
- 135 140 145 150 60. The system for giving continuously on a train an indication of traffic conditions ahead which comprises means upon the train for continuously supplying electric energy to the two track rails, means in the wayside for so effecting continuously a return transmission of said energy 135 over said track rails as to enable it to be received on the train to the exclusion of the energy supply transmitted directly from the train, means on the train for receiving the return transmission and for actuating a signal device to give a "clear" 140 indication, together with means in the wayside for passing an other than "clear" indication by suppressing the return transmission and thereby effecting the release of the signal device.
- 145 61. A pair of inductors for exciting the two 145 rails of a track circuit, a pair of inductors receiving current therefrom, means for continuously transmitting current from the exciting inductors through the track circuit to the receiving inductors together with means in said wayside 150

for transmitting the danger indication by interrupting the current thus transmitted.

62. The method of effecting the continuous control of a train in accordance with traffic conditions ahead which consists in continuously inducing energy into a pair of wayside inductors extending the length of a block, for the "clear" signal indication continuously transmitting said energy from a wayside point subject to control in accordance with traffic conditions ahead back onto the train by means of the same inductors as it is received from the train, operating thereby a signal device upon the train, and finally interrupting the flow of energy back to the train to give a signal indication on the train other than "clear".

63. In a train control system of the type in which energy is supplied to a wayside circuit from the train, the method of obtaining on board the train throughout each block section a continuous indication of the traffic condition ahead, which consists in continuously transmitting energy into the track circuit of a block section, receiving said energy at the far end of the block, retransmitting it in modified form through the track rails to the train, continuously receiving said energy on the train and operating thereby signal indicating means, and finally interrupting the flow of energy to indicate an other-than-clear-condition of the track ahead.

64. In the type of train control system wherein a source and a receiver of alternating current are both located on the train, the method of operation which consists in inducing current into a wayside circuit, transmitting said energy to a point of signal control in said wayside circuit, and finally so returning energy to the train receiving device over the same wayside circuit as to cause the train-carried receiving device to give a stop indication upon the occurrence of either a short-circuit or an open-circuit in the wayside circuit.

65. In a system for the automatic control of trains, the combination on the train of a source of alternating current, a transmitting inductor coil, a receiving inductor coil distinct from the transmitting inductor, a wayside circuit for receiving current from the train including an inductor and connections to switching means subject to traffic control, together with means included in said wayside circuit for effecting over the same wayside inductor a return transmission of current to the train-carried receiving device for maintaining a control signal.

66. In a train control system, the combination with track rails divided into blocks by insulating joints, of a track circuit for each block including a track relay, a railway vehicle, an alternating current generator on said vehicle, two transmitting inductors carried on the front end of said vehicle one over each rail and connected to said generator for transmitting energy flowing down one track rail and back through the other in said blocks successively as the train progresses, means located at the exit end of each block acting when supplied with said transmitted energy to continuously send return energy back to said vehicle through a circuit including said track rails, said means including a front contact of the track relay of the next block in advance and being effective to send return energy back to the vehicle only if said contact is closed, two receiving inductors carried by said vehicle one over one rail and the other over the other rail for inductively receiving said return energy to the exclusion of the transmitted energy, an amplifier

on the vehicle for amplifying the receiving return energy, and control means controlled by the amplified energy.

67. The combination with a vehicle track having insulated joints dividing the track into blocks, and a vehicle carried apparatus including a receiving coil cooperable inductively with said track, of trackside circuits including the track rails and having portions extending adjacent to the insulated joints to avoid "blind spots".

68. The combination with a vehicle track having insulated joints in the rails thereof dividing the track into blocks, and a vehicle carried apparatus including a receiving coil cooperable inductively with the track rails, of trackside circuits including said rails and conductors connected in series thereto and having portions extending adjacent to the insulated joints for cooperation inductively with said coil to avoid "blind spots".

69. The combination with a vehicle track having insulated joints dividing the track into blocks, and a vehicle carried apparatus including a receiving coil cooperable inductively with said track, of trackside circuits including the track rails and having loops with one side only thereof extending adjacent to the insulated joints to avoid "blind spots".

70. The combination with a vehicle track having insulated joints in the rails thereof dividing the track into blocks, and a vehicle carried apparatus including a receiving coil cooperable inductively with said rails, of trackside circuits including said rails and conductors connected in series thereto and having loops with one side only thereof extending adjacent to said insulated joints for inductive cooperation with said coil to avoid "blind spots".

71. The combination with a vehicle track having insulated joints dividing the track into blocks, and a vehicle carried apparatus including a receiver cooperable inductively with the track, of trackside circuits including the blocks of the track, said circuits having means at said insulated joints to energize said receiver to avoid "blind spots".

72. In train control apparatus, the combination with controlled trackside circuits including the track, the track having portions unsuitable for conducting electrical current, and vehicle-carried receiving means cooperable inductively with the trackside circuits, of means arranged to be energized and deenergized with corresponding trackside circuits and independent of and bridging said track portions for inductively influencing the vehicle-carried receiving means when it passes said portion, to avoid "blind spots".

73. The combination with a vehicle track having insulated joints in the rails thereof, controlled trackside circuits including said rails, and vehicle-carried receiving means cooperable inductively with said rails, of means separate from the rails arranged to be energized and deenergized with corresponding trackside circuits and bridging said insulated joints for inductively influencing the vehicle-carried receiving means when passing said joints.

74. The combination with a vehicle track having insulated joints in the rails thereof dividing the track into blocks, controlled trackside circuits including said rails of the blocks, and vehicle-carried receiving means cooperable inductively with said rails, of means arranged to be energized and deenergized with corresponding trackside circuits and arranged at said insulated joints for inductively influencing the vehicle-carried re-

ceiving means to avoid "blind spots" when said receiving means passes from one block to the next with the corresponding track circuits energized.

75. In train control apparatus, the combination with controlled trackside circuits including the track, the track having portions unsuitable for conducting electrical current and vehicle-carried receiving means cooperable inductively with

the trackside circuits, of means arranged to be energized and deenergized with corresponding trackside circuits and bridging said track portions for inductively influencing the vehicle-carried receiving means when it passes said portions, to avoid "blind spots" at said track portions.
